UNITED STATES PATENT OFFICE.

ALONZO L. BAKER, OF HERNDON, CALIFORNIA, AND RUSSELL L. BAKER, OF JOPPA, ALABAMA,
ASSIGNORS TO THE SOUTHERN PLOW CO., OF DALLAS, TEXAS, A CORPORATION OF
TEXAS.

CULTIVATOR.

No. 906,482.

Specification of Letters Patent.

Patented Dec. 8, 1908.

Original application filed May 11, 1906, Serial No. 316,419. Divided and this application filed July 16, 1908.
Serial No. 443,897.

To all whom it may concern:

Be it known that we, ALONZO L. BAKER, of Herndon, Madera county, California, and RUSSELL L. BAKER, of Joppa, Cullman county, Alabama, both citizens of the United States, have invented a new and useful Cultivator, of which the following is a specification.

This invention relates to cultivators and is 10 a division of an application filed May 11, 1906, Serial No. 316,419, said application having issued as Patent No. 833,660, of Oct. 16, 1906.

The object of the invention is to provide a 15 device of this character utilizing spring teeth which may be easily adjusted and which are so arranged as to reduce breakage to the minimum.

A further object is to provide simple and 20 efficient means for holding the teeth in adjusted positions without the necessity of perforating them so as to permit the passage of the securing bolts ordinarily employed, and which obviously weakens the teeth to a 25 considerable extent.

With these and other objects in view the invention consists of certain novel features of construction and combinations of parts which will be hereinafter more fully 30 described and pointed out in the claims.

In the accompanying drawings is shown the preferred form of the invention.

In said drawings: Figure 1 is a side elevation of the cultivator. Fig. 2 is a bottom 35 plan view thereof. Fig. 3 is an enlarged section on line A—B, Fig. 2. Fig. 4 is a rear elevation. Fig. 5 is a central vertical section through a portion of the cultivator. Fig. 6 is a section on line C—D, Fig. 5. Fig. 40 7 is a section on line E—F, Fig. 5.

Reference numeral 1 indicates the beam of the cultivator to which are bolted or otherwise secured the handles 2. Beneath the beam 1 and preferably somewhat to the rear 45 of its middle is secured the brace ring 3 the beam being recessed to allow receiving the brace ring and thereby its lower surface to be flush with the lower surface of the beam. A number of holes 4 are provided in the ring 3 50 to permit the adjustment of the bars 5, 6, 7, 8, 9, and 10 which carry the cultivator teeth 11. We preferably cause the bars 5 and 6 to lie in the same horizontal plane by offsetting one end of one of the bars and bolting their

inner ends with a single bolt to the beam 1. 55 As shown in the drawings this result is secured by making the bar 5 straight and by offsetting the bar 6 at its inner end where it crosses the bar 5, as shown. The upper rear bars 7 and 8 are made to lie in the same plane 60 with one another and with bars 5 and 6 by a similar construction, the bar 7 being straight and the end of the bar 8 offset as shown.

Beneath bars 7 and 8 we provide additional strengthening bars 9 and 10 the bar 9 65 being offset where it crosses bar 10. The bars 7 and 8 are fastened to the beam by a single bolt, the head of which is sunk into a recess in the bar 7.

The cultivator teeth 11 are bolted to the 70 bars 5 and 6 by bolts 12, the bolts being placed with their tapped ends uppermost so that should a nut work loose it will be readily noticed and when any adjustment of the device is made the nuts will be readily accessible. 75 Especial attention is directed to the fact that our cultivator is so constructed that every bolt in the frame work may thus be placed with its tapped end uppermost a construction which reduces the danger of 80 breakage because of the nuts working loose and which makes our device readily accessible by adjustment.

The cultivator teeth 11 are not perforated for the passage of bolts through bars 7, 8, 9, 85 and 10 since we have found that such a construction makes the teeth very liable to break. To remedy this defect we provide depressions 13 in the teeth 11 as by stamping them therein before tempering and also provide corresponding projections on the lower 90 rear bars 9 and 10 which fit snugly into the depressions in the cultivator teeth. This construction makes a strong joint and dispenses with any necessity of breaking the 95 fiber either of the teeth 11 or of the bars 9 and 10 by making holes therein.

Bolts 14 are passed through the bars 7, 8, 9 and 10 respectively to secure them together. Between the said bars there are only the 100 teeth 11 to hold the bars apart so that it is possible to secure the teeth therebetween as tightly as is desired. Braces 15 are arranged at opposite sides of the beam and are secured at one end to the inner bolts 14, the 105 other ends of the braces being secured to the beam 1 on top thereof and by the same bolt which secures the bars 7 and 8 thereto.

The bolts 14 securing the bars 9 and 10 to the braces 15 also pass through bolt holes in the brace ring 3 and thus secure the bars firmly in position. Nuts or washers 14' are placed 5 between the bars 7 and 8 and the brace ring 3 so that the bars 5, 6, 7, and 8 and the bolts and nuts thereon may pass readily below the brace ring. Links 16 are bolted to the front and rear bars on each side respectively to 10 hold the sets of bars in parallelism.

We have placed the bolts which pivotally secure the rear cross bars 7, 8, 9 and 10 to the beam 1 at substantially the center of the brace ring 3 and the forward cross bars 5 and 15 6 are pivoted to the beam at a point in advance of the point at which the rear bars are secured thereto. By this construction we are enabled to firmly support the cross bars in any position and particularly so in the ordinary or "A" position of the cultivator. 20

From the foregoing description the operation of our improved cultivator will be apparent without further detailed statement.

It is to be understood of course that 25 various changes may be made in the structure without departing from the spirit or sacrificing the advantages of the invention.

What is claimed is:

1. The combination with a beam and a 30 brace ring secured thereto; of front bars pivotally connected to the beam and extending beyond opposite sides thereof, teeth pivotally connected to said bars and extending rearwardly therefrom, upper and lower 35 strengthening bars pivotally connected to the beam at the center of the ring, said teeth being mounted to move laterally between the upper and lower strengthening bars, thelapping portions of the bars and teeth being 40 imperforate, said lapping portions of the teeth and bars having integral interlocking pivot means, and means removed from the teeth for binding the rear strengthening bars upon opposite faces of the teeth. 45

2. The combination with a tongue and a brace ring secured thereto; of front bars pivotally connected to the tongue and extending beyond opposite faces thereof, teeth pivotally connected to said bars and extending 50 rearwardly therefrom, upper and lower strengthening bars pivotally connected to the beam at the center of the ring, said teeth extending between the upper and lower bars, means extending through the upper and 55 lower strengthening bars and removed from the teeth for clamping the bars upon the teeth, thelapping portions of the teeth being imperforate, and interlocking pivot means upon the teeth and one of the bars for holding 60 said teeth against lateral movement between the bars and in position parallel with

the beam but permitting swinging movement of the teeth relative to the bars.

3. The combination with a beam and a brace ring secured thereto; of front bars pivotally connected to the beam and extending beyond opposite faces thereof, teeth pivotally connected to said bars and extending rearwardly therefrom, upper and lower rear strengthening bars pivotally connected to the beam at the center of the ring, said bars being disposed parallel with the front bars, bolts extending transversely through the upper and lower bars, certain of said bolts being extended through the ring and detachably 65 engaging the same, said teeth being parallel and extended between the upper and lower bars and between the bolts, thelapping portions of the teeth and the upper and lower bars being imperforate, and interlocking 70 pivot means upon the teeth and certain of the bars for holding the teeth against lateral movement relative to the bars but permitting swinging movement of the teeth relative to the bars. 75

4. In a cultivator the combination with a front bar pivotally supported and upper and lower rear strengthening bars pivotally mounted at one end; of teeth pivotally connected at their front ends to the front bar 90 and extending between the upper and lower strengthening bar, there being recesses in one of the strengthening bars, outstruck projections upon the teeth and pivotally mounted within the recesses, and means for binding 95 the strengthening bars upon opposite faces of the teeth, those portions of the teeth between the bars being imperforate.

5. A cultivator comprising a pivotally mounted front bar, upper and lower strengthening members pivotally mounted at one end and in rear of said bar, a series of members pivotally connected to the bar and extending between said upper and lower members and constituting teeth, there being interlocking 100 projections and recesses upon said members constituting pivotal connections therebetween, and means extending through the upper and lower members for binding them upon opposite faces of the toothed members. 105

In testimony that we claim the foregoing as our own, we have hereto affixed our signatures in the presence of two witnesses.
